UNITED STATES PATENT OFFICE.

JAMES T. O'CONNOR, OF CHICAGO, ILLINOIS.

ADVERTISING-CHAIR.

993,397.

Specification of Letters Patent. Patented May 30, 1911.

Application filed February 28, 1910, Serial No. 546,409. Renewed February 18, 1911. Serial No. 609,339.

To all whom it may concern:

Be it known that I, JAMES T. O'CONNOR, a citizen of the United States, residing at Chicago, county of Cook, and State of Illinois, have invented certain new and useful Improvements in Advertising-Chairs, of which the following is a specification.

My invention relates to improvements in advertising chairs and has for its object the production of a chair of this nature which shall be of simple construction and efficient in its operation. The invention consists in the combination and arrangement of parts hereinafter described and claimed.

15 The invention will be more readily understood by reference to the accompanying drawings forming a part of this specification, and in which,

20 Figure 1 is a perspective view of a chair embodying my invention, Fig. 2 is a partial side elevation of a chair with portions broken away, Fig. 3 is a section on line $x-x$ of Fig. 2, Fig. 4 is a partial top plan view of an arm of the chair with portions 25 broken away, and Fig. 5 is a perspective view of the upper end of the operating bar of the device illustrating the co-operation with a ratchet wheel for operating the advertising sheets.

30 The preferred form of construction as illustrated in the drawings comprises a rocking chair 1 which may be of any usual or desired construction, provided with front and rear posts 2 and 3. One of the rear 35 posts 3 is provided with a vertically disposed passage or channel 4 closed on the rear side by means of a cover plate 4'. In passage 4 is mounted a vertically reciprocating operating bar 5 having an enlarged lower and

40 upper end 6 and 7. The lower enlarged end 6 projects from the passage 4 through the bottom of the rocker of the chair to contact with the floor or other supporting surface upon which the chair rests. A pin 8 is 45 passed through passage 4 in position to contact with the lower edge of the upper enlargement 7 to limit the downward movements of bar 5. The upper enlargement 7 carries a gravity operated pawl 9 adapted

50 to coöperate with a ratchet wheel 10 secured to a shaft 11 traversing the back of the chair. Each of the arms 12 of the chair is provided with a longitudinally extending channel 13 communicating at the rear with the corresponding passage 4. Rollers 14 are se-

cured at either end of shaft 11 and registering with the rear ends of channels 13. Idler rollers 15 are mounted in the forward ends of channels 13 and an advertising sheet is passed over rollers 14 and 15 as 60 shown. Channels 13 are closed on their upper side by means of glass plates 17 which protect the advertising sheet and through which the same is visible to an occupant of the chair. Each of the arms 12 is reinforced 65 by channels 18 secured thereto and which also serve to hold plate 17 in position.

In operation it will be observed that as the chair is rocked by an occupant the bar 5 will be caused to reciprocate vertically 70 and pawl 9 will operate to cause intermittent rotation of shaft 11 and rollers 15. This causes intermittent feed of advertising sheet 16 so that the advertisements thereon will be constantly changed as the chair is 75 rocked by an occupant. It will be observed that the operating mechanism is very simple and inexpensive of construction and operates without the aid of a spring so that it will be exceedingly durable and reliable. 80

While I have illustrated and described the preferred construction for carrying my invention into effect, this is capable of variation or modification without departing from the spirit of my invention. I therefore do not wish to be limited to the exact details of construction set forth but desire to avail myself of such variations and modifications as come within the spirit and scope of the appended claims. 85

Having described my invention what I claim as new and desire to secure by Letters Patent is:

1. In a rocking arm-chair, a shaft traversing the back of the chair; a pair of rollers carrying an advertising sheet in each of the arms of said chair, the rear rollers of each pair being mounted upon said shaft; a ratchet wheel on one of said rear rollers; and a vertically reciprocating member 95 adapted to contact with the floor and carrying a pawl arranged to operate said ratchet wheel, substantially as described.

2. In a rocking arm-chair provided with a rear post having a vertically disposed passage, a shaft traversing the back of said chair; a pair of rollers carrying an advertising sheet in each of the arms of said chair, the rear rollers of each pair being mounted upon said shaft; a ratchet wheel on one of 100 105 110

the rear rollers; a bar slideable in said passage and adapted to contact with the floor at its lower end; a gravity operated pawl at the upper end of said bar adapted to operate said ratchet; and a stop adapted to limit the downward movements of said bar, substantially as described.

In testimony whereof I have signed my name to this specification in the presence of two subscribing witnesses.

JAMES T. O'CONNOR.
